UNITED STATES PATENT OFFICE.

NILS PETERSON, OF MOSCOW, IDAHO.

VALVE-ACTUATING MECHANISM.

1,177,963.

Specification of Letters Patent.

Patented Apr. 4, 1916.

Application filed July 25, 1914. Serial No. 853,138.

To all whom it may concern:

Be it known that I, NILS PETERSON, a citizen of the United States, residing at Moscow, in the county of Latah and State of Idaho, have invented a new and useful 5 Valve-Actuating Mechanism, of which the following is a specification.

The device forming the subject matter 10 of this application is a float-controlled valve for a flushing tank and the present invention aims to provide, in combination with a float 15 of novel form, a means whereby the position of the float-carrying lever may be adjusted through the instrumentality of elements on 20 the stem of the valve.

In the drawings—Figure 1 is a longitudinal section through the front wall of a tank showing the present invention in operable 25 relation therein, a portion of the parts being shown in section to better illustrate the incased parts. Fig. 2 is a top plan view of the tank with the complete mechanism 30 therein.

Referring to the drawings, the numeral 1 35 designates a casing which is open at the lower end to receive a bottom member 2 which carries a metal tank 3, set screws 2' being provided to lock the bottom 2 and the tank 3 within the casing 1.

The flushing pipe 4 of the present mechanism is provided with a seat 5 for the 40 reception of a buoyant valve 6, preferably made in the shape of a hollow rubber ball. A tube 7 is connected to the seat 5 and constitutes an overflow directing member, the 45 open upper end of the tube being located above the highest water level in the tank 3, the lower end of the pipe 7 being in communication with the pipe 4 below the valve seat 5. A stem 11 is carried by the ball 6 and is disposed in coöperating relation with a stem 10 connected to the inner free end of a lever 12, provided with a weight 16 which assists in the seating of the valve 6. The 50 lever 12 is pivoted at 13 so that its free end may be depressed by a manually controlled lever 15, which is accessible from the exterior of the tank 3.

A supply pipe 18 is connected to a 55 coupling member 19 which is provided with an inverted valve seat 20. A casing 21 constitutes a stand pipe and supporting member, and is connected upon the inner side of the tank 3 to the coupling 19, the casing 21 being provided with a spout 22 which is in

communication with an overflow outlet 23. A tube 9 is connected to the spout 22 and has its terminal 8 disposed within the upper end of the tube 7 so that the after flushing water may be directed into the tube. 60

A tube 24 is connected to and forms an upward extension of the casing 21 and constitutes a guide for a valve stem or rod 25 carrying upon its lower end within an enlarged portion of the supply pipe 18, a valve 26 for controlling the seat 20. The upper end of the stem 25 is threaded and extends beyond a coupling 27 mounted on the tube 24, the coupling being provided with two 65 upward arms 28 and 29. The arm 29 is 70 provided with an aperture for the reception of a pin 30 which forms a fulcrum for a lever 32, receiving the threaded end of the stem 25. The threaded end of the stem is adjustably connected to the lever 32 to cause 75 the rise and fall of the valve 26, by means of nuts 33 and 34. A link 32' connects the lever 32 with a lever 31, the latter being fulcrumed on the arm 28. A weight 35 is 80 adjustably mounted along the lever 31, and adjustably connected beyond the lever is a sleeve 36 carrying an ovoidal hollow float 38, which has freely movable therewithin, a plurality of rolling elements 39, which may be inserted into the float 38 through an opening 50 in the top of the float, the opening 85 50 being closed by a cap 51.

It will thus be seen that when the ball valve 6 is elevated by the levers 12 and attendant parts to release the water within 90 the tank, the float 38 will move downwardly and consequently lower the valve 26 to permit water to enter through the spout 23 into the tank 3. When the ball valve 6 automatically seats, the water within the tank 95 will rise due to the entrance thereof through the spout 23 and will gradually elevate the float 38 and operate the lever 31 so as to bring the valve 26 gradually toward the seat 20. 100

The number of weights 39 within the float 38 may be changed as occasion may demand, the opening 50 and the cap 51 being of use for this purpose.

What is claimed is:

In a device of the class described, a tank; 105 an inlet valve casing assembled with the tank, the casing having a valve seat and being provided with an outlet discharging into the tank; a valve controlling the seat; a 110

stem assembled with the valve; a lever mechanism; a fulcrum for the lever mechanism; a float having a weight-receiving opening; a weight in the float and adapted to be introduced thereinto through the opening; a rigid connection between the float and the lever mechanism; and nuts threaded onto the stem and engaging the upper and lower edges of the lever mechanism, the nuts being adjustable to vary the relative posi-

tion of the lever mechanism and the float when the valve is engaged with the seat.

In testimony that I claim the foregoing as my own, I have hereto affixed by signature in the presence of two witnesses.

NILS PETERSON.
